UNITED STATES PATENT OFFICE.

IVORY HAZELTON, OF BOSTON, ASSIGNOR OF ONE-HALF TO LEVERETT SALTONSTALL, OF NEWTON, MASSACHUSETTS.

CAR-COUPING.

SPECIFICATION forming part of Letters Patent No. 378,311, dated February 21, 1888.

Application filed November 21, 1887. Serial No. 255,722. (No model.)

To all whom it may concern:

Be it known that I, IVORY HAZELTON, of Boston, in the county of Suffolk and State of Massachusetts, have invented a new and useful Improvement in Car-Couplers, which will, in connection with the accompanying drawings, be hereinafter fully described, and specifically defined in the appended claims.

In said drawings, Figure 1 is a top plan view of a coupler embodying my invention. Fig. 2 is an elevation of the coupler shown in Fig. 1, taken as viewed from the bottom of the sheet. Fig. 3 is a horizontal section taken as on line Z Z, Fig. 2, and viewed as from above that line. Fig. 4 is a side elevation viewed from the left in Fig. 1. Fig. 5 is a detached top plan view of the draw-bar and the detaching-cord.

My invention relates to that class of couplers which are more especially intended to be secured to the rear end of the "tender," and by which the engine is coupled to the train of cars; and it consists in features of novelty hereinafter fully described, and pointed out in the claims.

Referring again to the drawings, A represents the frame of the coupler, which is preferably formed as an entire casting, and with a base-plate, b, through and by which it is rigidly bolted to the tender, and also having the two wings or flanges c c, which converge and unite at their upper portion, forming, with the raised portion of b, the box-like part d, that is covered by the foot-board g. In said raised portions d is arranged the buffer e, which is cushioned by the helical spring f. Said parts thus far specified, being well known, need not be further described except in connection with the parts invented by me.

B represents the draw-bar, having a head, h, secured thereto by pivot i. Said bar extends through base-plate b, and is pivotally secured by bolt j to the V-like stay C, which is secured to and extends from base-like plate b. Said base-plate b is cut away at k, Fig. 3, to allow a vibrating movement of bar B upon its securing bolt j, it being habitually held in constant contact position, as there shown, by spring l, secured in flange c of frame A, which spring is adjustable in its stress by means of

screw m. A bar-like portion, n, of head h extends into a slot in bar B, and at its end has a seat, p, formed in it, to receive the correspondingly-formed detent s, which is habitually engaged therewith by helical spring t, 55 the locking-lip q of part n being rounded away on its outer face to serve as a cam to force detent s inward against the stress of its spring when head h is being closed from the open position shown by dotted lines in Fig. 3. 60

For the purpose of detaching the coupler a cord, v, is secured to detent s by means of stud u, said cord being carried to the cab, so as to be in convenient reach of the engineer and fireman, who, by drawing thereon, disconnect the detent from lip q, when the movement of the engine and tender will by the contact of head h with the coupler of the adjacent car swing the head into the position indicated by said dotted lines, thus freeing the engine 70 and tender from the car, while the contact of the car-coupler with bar-like part n when the head h is swung open will close it to the position shown by solid lines in Fig. 3, thus coupling the engine and tender to the car. 75

As a precaution against the uncoupling of the tender and car when rounding very sharp curves, I provide a locking-block, D, mounted to slide upon one of the wings c, as shown, and secured thereon by screw w, passing 80 through a slot in the block, so as to allow a free vertical movement thereof, which movement is effected by the engineer or fireman by means of cord 3, which extends into the cab, and is also attached to the vertical arm of bell-crank z, that is pivoted at z to stud y, secured to frame A, the opposite or horizontal arm of said lever being pivoted at 2 to said locking-block D. 85

It will be obvious that, instead of retracting 90 detent s by direct connection of cord v therewith, a lever may be interposed between it and said detent, whereby less force on the part of the operator will effect the same result, and draw-bar B may have an elastic instead of a rigid support, as shown, if preferred; and various other changes in the several details of construction may be made without departing from the spirit of my invention. 95

I claim as my invention—

1. The combination of draw-bar B, its laterally-vibrating head *h*, formed with seat *p*, and lip *q*, detent *s*, spring *t*, and cord *v*, all substantially as specified.
- 5 2. The combination, with frame A and draw-bar B, of locking-block D, formed with a vertical groove to receive a flange, *c*, of said frame, and with an elongated slot to receive the securing-screw *w*, and the angle-lever *x*, pivoted upon frame A, and having one of its arms pivotally connected with said block, and cord 3,
- 10 attached to the other arm of said lever, all substantially as specified.
3. The combination, with frame A and draw-bar B, pivoted to stay C, of spring 1, seated in a passage in frame A at right angles to said bar, and provided with the adjusting-screw *m*, substantially as specified.

IVORY HAZELTON.
